UNITED STATES PATENT OFFICE.

EDMUND O. SCHWEITZER, OF CHICAGO, ILLINOIS.

OVERLOAD-CIRCUIT-BREAKING APPARATUS.

1,340,917.

Specification of Letters Patent. Patented May 25, 1920.

Application filed January 10, 1919. Serial No. 270,483.

To all whom it may concern:

Be it known that I, EDMUND O. SCHWEITZER, a citizen of the United States, and resident of Chicago, in the county of Cook and State of Illinois, have invented a new and Improved Overload-Circuit-Breaking Apparatus, of which the following is a full, clear, and exact description.

My invention relates to overload circuit breaking apparatus, and more particularly to means for interrupting current flow at high tension.

The object of my invention is to provide a novel method of and means for switching and particularly for interrupting the flow of high tension current with simple and inexpensive apparatus. Other and subsidiary objects will be apparent from the following specification.

The switching or interrupting of current flow on circuits operating on high tension is in general a difficult and dangerous matter. When a line bears a heavy flow of current at a high voltage, physical separation of the conductors is followed by an arc which tends to persist to a degree depending upon the resistance and inductance of the circuit, the capacity of the generating system back of it, and the voltage on the conductors.

In practice previous to my invention, the only feasible way to switch such current flow was by oil switches, but oil switches are very expensive in cost and upkeep and in large sizes are slow to operate. The use of air break switches for such service has been wholly unpracticable heretofore. The reason for this is that the arc which is formed destroys the switch contact. Particularly upon a shorted or overloaded line an air break switch is useless because when the blade is opened, the arc follows the full movement of the blade and continues even after the switch is fully opened. The result is the prompt destruction of the switch. This is readily understood when it is considered that on a short-circuited line substantially the entire capacity of the system is concentrated upon the production of heat, and as the break at the switch constitutes the major part of the resistance of the circuit, an enormous amount of heat may be liberated at the switch.

The provision of oil switches at various points on a line or system where it is desirable to have means for opening the cir-

cuit, is not feasible, because of first cost and further because of the inability to give them proper attention for maintenance. As a result, most lines are inadequately provided with circuit breakers.

The statements above made with respect to an air break switch also holds true of any type of switch, the voltage interrupting capacity of which is below that of the circuit upon which it is to be used, whether of air break switch, oil switches or any other type.

According to my invention I provide a switch which, of itself, is incapable of satisfactorily interrupting the flow of current at the voltage at which the line is operated and by means of a fuse of special character in shunt with the switch I am able to take from the switch the actual duty of interrupting the current flow and place it upon the fuse, which fuse is of such character and construction as to be capable of interrupting the flow of current at the voltage to which the line is subjected.

In the preferred form of my invention I employ an air break switch of relatively inexpensive construction and of a voltage interrupting capacity lower than that required to break a heavy flow of current on the line, and place in shunt of this switch a fusible circuit breaking device of high voltage interrupting capacity but of small current carrying capacity. The fusible circuit breaking device which I employ is preferably of the type shown in the patent to myself and Mr. Conrad, No. 1,135,548, although any fuse of similar characteristics and ability to positively interrupt the circuit may be employed instead. This type of fuse is particularly valuable because of being surrounded by liquid. It is capable of carrying a large overload current for a very short period of time without fusing, thus permitting the switch to open far enough to prevent reformation of the arc at the contact of the switch, and also because of the ability to positively interrupt the flow of current at this fuse.

The fuse may be connected normally in circuit in shunt with the switch, or it may be connected in a shunt which is closed only when the switch opens with a certain time lag intervening. In the latter construction the fuse will be kept out of the normal flow of current and will be relatively cold so that it will not blow immediately, but will permit the switch to move to open position so

that after blowing of the fuse, the voltage of the line will not be able to reestablish the arc.

In this particular embodiment, the fuse is preferably of slightly larger current carrying capacity than where the fuse is normally in circuit. Broadly considered, my invention comprises a novel method of interrupting the flow of current in a conductor which consists in mechanically interrupting the conductor and transferring the current flow to a fusible conductor out of range of the influence of said mechanical interruption, then causing the current flow to fuse the parallel conductor and then interrupting the arc at the fuse by interposition of a dielectric medium of great strength.

In the accompanying drawings:

20 Figure 1 is a diagrammatic view of high tension three phase power or lighting circuit provided with over-load circuit breaking apparatus embodying my invention;

25 Figs. 2 and 3 are views of the preferred and modified form of my apparatus, respectively;

30 Fig. 4 is a longitudinal section of the fuse in normal condition, which fuse is employed by my invention;

35 Fig. 5 is a similar view of the fuse in operation;

40 Figs. 6, 7 and 8 are transverse sections taken on corresponding sections indicated in Fig. 4;

45 Fig. 9 is a front elevation of a modified form of switch embodying my invention;

50 Fig. 10 is a side elevation of the same; and

55 Fig. 11 is a fragmentary plan view of the same.

In the drawings I have shown the line conductors 1, 2 and 3, representing the three high tension lines or conductors of a three-phase system supplied by dynamo or generators 4. The conductors 5, 6 and 7 are other line conductors leading off from the conductors 1, 2 and 3, the conductors 5, 6 and 7 being understood to run through some suitable transmission device or other apparatus requiring overload current protection.

60 Each of the lines 5, 6 and 7 I show equipped with automatic over-load circuit breaking apparatus involving my present invention. I show in connection with line or conductor 5, for example, the fuse 8 which is of very low carrying capacity, preferably a very small percent., for instance one percent., of the entire carrying capacity or load carried by conductor 5.

65 I also show a circuit breaker 9 which may be any suitable or desirable type of automatic commercial circuit breaker preferably of the air break type. The contacts 10—10 of this circuit breaker are connected by wires 11 and 12 with the line 5 so that the fuse 8 is

in shunt of the circuit breaker. The operating solenoid 14 of the circuit breaker is connected in series with the line conductor 5, this solenoid 14 acting upon tripping mechanism 15 to operate the circuit breaker when a predetermined overload traverses the conductor 5. Thus it will be seen that whenever a predetermined or sufficient overload passes in the line 5 the solenoid 14 will actuate the circuit breaker 9 and thereby open the circuit across the contacts 10—10, whereupon the entire current will be thrown upon the fuse 8, thereby operating or blowing said fuse instantaneously, the fuse having a relatively small carrying capacity. The other lines 6 and 7 I show also provided with fuses 8—8 and circuit breakers 9—9 connected and operating as described in connection with line 5. It will be seen that reliability, certainty and quickness of action are secured, the circuit breaker operating quickly when a predetermined overload is reached and then the fuse operating. Thus, with a low voltage circuit breaker of small and cheap design and a low capacity fuse of high voltage, a very rapid operating mechanism is obtained with reliability of action and low maintenance cost. It will be seen at the same time that the arcing effect is taken care of by the character of the arrangement of circuit breaker and fuse, and protection for the translating apparatus on the line is thereby insured for the circuit breaker with its tripping coil in the primary circuit is more responsive and will operate more quickly than the usual oil switch and tripping mechanism at the generating stations. This permits the circuit breaker out at the consumer's premises to open the line before the main oil circuit breakers at the central station are tripped. Better operating of the entire system is thereby secured.

When desired, the circuit breaker may be immersed in oil, although as a general rule this is not necessary because there is no little arc. With the arrangement as shown in my invention, it is easy and inexpensive to replace the fuse since it is contained in a removable cartridge as will be explained later.

In Fig. 2 I have shown the preferred form of apparatus which I employ. This embodies a swinging knife blade switch 16 pivoted at 17 to a post 18 secured to an upright support 19. The blade 16 has an extension 20 to which is secured a spring 21, also fastened to the support 19, said spring tending to draw said extension 20 toward the support 19. This upright support is made of insulation. Spring contact jaws 22 are also mounted upon the upright support 19 and are arranged to coöperate with the blade 16 and other contact jaws 23 also mounted on the support 19 are arranged to coöperate with the extension 20. These contacts are suitably insulated from each other. An elec-

tromagnet or solenoid 4 is shown mounted upon the support 19, being conveniently associated with the jaws 22 and is provided with an armature 25. This armature 25 is 5 pivotally connected at its lower end to a support 26 and at its upper end constituting a support for the links 27 and 28 which are pivotally connected to one another, by frictionally engaging the under sides of the links 10 at their pivotal point to retain the links in the position disclosed in Fig. 2, it being understood that the link 27 is in the form of a hook or catch to engage the end of the switch blade 16. A spring 29 acts upon the 15 catch 27 tending to hold the same in engagement with the switch blade 16. Thus, the blade 16 is normally held closed in the contact 22 by the catch 27, but when the solenoid 24 is actuated and the armature 25 attracted, 20 the catch 27 being shifted due to the action of the spring member 29 so as to disengage the blade 16, thereby permitting the spring 21 to actuate the same and separate the blade 16 from the contact 22 and cause extensions 25 20 to connect with the contact jaws 23, the links 27 and 28 having a loose connection 25 with one another and with the armature 25 with sufficient loose motion to permit a slight buckling of the links 27 and 28 so as to 30 cause a release or trip of the blade 16.

On the other side of the upright 19 are mounted a pair of posts 30 and 31 which support an inclosed fuse 32, the construction of which is shown in Figs. 4 to 8 and 35 will be described later. The arrangement is so connected that the solenoid 24 is included in the circuit as shown in Fig. 1, and when the solenoid is energized by an overload current and the blade 16 released, the circuit 40 through the blade 16 by way of contact jaws 22 is opened, and the fuse 32 is connected in shunt by the extension 20 meeting the spring jaws 23, the connection to the swinging blade 16 and extension 20 being by way of metal 45 rods to posts 18.

In this embodiment of the invention, the fuse 32 is not normally in circuit, and hence is not subject to being heated by current flowing during normal operation. A further advantage of this form lies in the lag 50 between the opening movement of the switch and the connection of the fuse in shunt. Unless the resistance and circuit carrying capacity of the fuse are carefully proportioned 55 to coöperate with the voltage and opening action of the fuse, there is a tendency when the fuse is permanently in shunt for the fuse to blow before the switch is far enough opened to prevent the arc being re-formed 60 at the switch. In the form of apparatus which I employ, the liquid submerged fuse overcomes this tendency to blow immediately, to a noticeable extent and is an important feature of the invention. In the 65 preferred form of Fig. 2, the switch gets an

opening motion sufficient to overcome such tendency even if the fuse is not of the liquid submerged type.

The particular fuse which I employ is shown in detail in Figs. 4 to 8 inclusive. 70 This fuse is of the inclosed type and it is provided with special means to extinguish the arc, this means comprising an arc extinguishing liquid of high dielectric strength such as carbon tetrachlorid. The fuse comprises a sleeve of glass or other insulating material 40 having brass ferrules 41 and 42 at top and bottom, which ferrules are cemented in place on the sleeve. A fusible element 43 inclosed in a cork barrier 44 is 75 connected to a removable vent or disk 45 by a link 46. The vent or disk 45 is soldered on the upper ferrule and is adapted to be blown off in the case of vigorous blowing of the fuse. The lower end of the fusible element 43 is connected by a link 47 to a cross-bar 48, which cross bar is mechanically connected to the wooden liquid director 49. A link 50 connects the cross-bar to a helical spring 51, the lower end of which is connected to the lower ferrule 42. A flexible cable 52 is connected in shunt of the spring 51 to prevent overheating and destruction of the temper of the spring. The entire sleeve is filled with carbon tetrachlorid or 95 other similar suitable insulating material. When the element 43 is fused, the spring draws the terminal or link 47 down into the sleeve and at the same time the liquid is projected in a stream by the liquid director 49, as shown in Fig. 5, thus positively 100 interrupting the flow of current. The fusible element 43 is made of a small percent. of the carrying capacity of the main switch to which it is connected in shunt. The resistance is also preferably made sufficiently high so that if the element is normally connected in shunt of the switch, the flow of 105 current through it will be small enough not to blow the fuse under all conditions of current flow to which it is subjected when the switch blade is still closed. The submergence of the fuse also gives it a greater heat-absorbing ability so that actual blowing is delayed until the movable blade has had an 110 opportunity to leave the stationary contact. This is highly beneficial in that it permits the switch to move farther toward the open position and thus get farther out of range of the fixed contact before the fuse actually blows. After the fuse once blows the 115 arc which is caused by such blowing is extinguished almost instantaneously.

Operation of the complete device, shown in Fig. 3 and diagrammatically indicated in Fig. 1, is as follows:

When the switch blade is released by automatic or manual operation of the catch the blade begins its opening movement and tends to draw an arc. After the blade has 130

reached a predetermined position the rear end of the blade connects with the fuse 32 in shunt of the break at the switch contact and the current flow is established through the fuse. The fuse then blows and positively stops the flow of current by interposing the arc extinguishing liquid which is a medium of high dielectric strength between the separated terminals of the fuse.

10 The fuse and switch are separated by insulating barriers consisting of the insulating support 19 and also the sleeve 40 to prevent mutual interaction between the fusible element and the switch, and particularly to prevent the arc at the fuse from reestablishing the arc through the switch.

15 In Fig. 3 I have shown an arrangement very similar to that of Fig. 2, but instead of having three posts on the upright 19 I have 20 shown in Fig. 3 only two posts, namely, the spring jaws 22 and the post 18 to which the switch blade 16^a is pivoted. The fuse 32 is connected with the posts 30, as in Fig. 2, and also with the posts 31^a, being a rear extension of the post 18. Thus a fuse 32 is normally connected in shunt with the circuit breaker or switch instead of being thrown into shunt by the operation of the switch as in Fig. 2.

25 30 In Figs. 9 and 10 I have illustrated a modification of my invention suitable for use in connection with certain well known indoor disconnecting switches. The switch shown comprises the upper terminal 60 and the lower terminal 61, consisting of a metal head having a screw threaded shank adapted to be secured in a suitable partition or mounting as is customary in indoor inclosed switches of this character. The head 65 has 35 a plurality of fins or plates 66 secured thereto, these plates forming the hinge for the movable blade members 67, which in this case are shown as three in number. The upper block 64 has a plurality of similar fins or plates 68 secured thereto for making contact with the free ends of the switch blades 67.

40 45 A hinge pin or bolt is passed through the hinge plates 66 and through the lower ends of the blades 67 to form the pivots for the movable blades. The movable blades are thus gripped between pairs of the hinge plates and held in place yieldingly by means of the spring washers and the bolts 69.

The blades are provided with a suitable 50 eye or other engaging portion by which the switch may be manually opened or closed.

55 I connect the fuse 72 in parallel with the switch. The upper ferrule 73 of the fuse 72 is mounted in a suitable contact clip 74 which in turn is supported from a bar of insulation 75 which holds the upper contact clip 74 and connected parts at a suitable distance and in suitable alinement with respect to the lower contact clip 76. The lower contact clip 76 which engages the fuse ferrule

77 is mounted upon a suitable bracket 78 which connects electrically with the pivot plate 66 through the bent or U-shaped connecting member 79, which has its outer end bolted to the bracket 78 by means of the bolt 80. The inner end of the U-shaped member 79 is fastened under the adjacent spring washer 70 and is pivoted upon the bolt 69. A similar U-shaped member 81 is connected at the upper end of the bar of insulation 75 and the clip 74 is connected to said U-shaped member 81 by the bracket 82 and the bolt 83. The inner end of the U-shaped member 81 forms a movable switch contact element which engages between the outermost plate or fin 68 and an added plate or fin 84 which is bolted to the side of the block 64. A suitable eye 85 is bolted to the U-shaped member 81 by the bolt 86 so that the insulating bar 75 with its attached part may be swung about the pivot pin 69.

50 The fuse 72 is of the type and character illustrated in the previous figures. It is mounted on a swinging blade of insulation 72 so that the upper end of the mounting 90 may be disconnected from the upper terminal 60 which preferably is the live terminal so that the fuse may be withdrawn and replaced without incurring the danger of contact with live parts.

55 60 The operation of this form of device is as follows: Assuming that the switch is closed and that the fuse is connected in place, interruption of the flow of current is accomplished by inserting a hook in the hole in the eye 71 and pulling the switch blades 67 outwardly into the position shown in Fig. 10. The current is diverted to the fuse 72 and for an appreciable period of time the current is shunted through said fuse so that very 100 little arc occurs at the separation of the blades 67 from the contact 68, and after the blades have been moved outward far enough so that the voltage will not reestablish the arc the fuse 72 blows, positively interrupting 105 the connection between the switch terminals. The operating hook may then be inserted in the eye 85 to disconnect the terminals of the fuse so that the fuse may be withdrawn and replaced with a fuse in the set condition.

110 115 It will be apparent from the above description and from the drawings that this form of construction permits the addition of certain parts to standard switches so that my invention may be applied to switches already in use.

120 It will be understood that changes and modifications may be made without departing from the spirit of the invention.

125 What I claim is:

1. The method of interrupting a flow of current in a conductor which comprises mechanically breaking the conductor, conducting the current flow wholly through a fusible element independent of the break, fusing 130

the fusible element and interrupting the flow of current at said fusible element by interposing a fluid dielectric of greater strength than that prevailing at the mechanical break.

2. The method of interrupting the flow of current in a conductor which comprises mechanically breaking the conductor, conducting the current flow wholly through a fusible element independent of the break, fusing the fusible element a short interval of time after the opening of the switch, and promptly interrupting the flow of current at said fusible element by interposing a dielectric of greater strength than that prevailing at the mechanical break.

3. The method of interrupting the flow of current in a conductor which comprises mechanically breaking the conductor, conducting the current flow wholly through a fusible element independent of the break, cooling the fusible element with a liquid dielectric to delay the operation of the same, then fusing the fusible element and interrupting the flow of current at said fusible element by interposing said liquid dielectric.

4. In combination, an air break switch having means for opening the same, a fusible element, means for connecting the fusible element across the terminals of the switch when the switch is opened, a barrier of insulation between the fusible element and the switch to prevent mutual interaction between the fusible element and the switch, and means for interposing a dielectric medium of greater strength than air between the terminals of the fuse after the same closes.

5. In a device for interrupting a current flow at high voltage, a switch of less interrupting capacity than that required to break the flow of current at said voltage, a fusible element and means for connecting the fusible element across the terminals of the switch, said fusible element being submerged in a liquid of relatively great dielectric strength to permit a slight delay in the fusing of the element and to positively extinguish the arc at the fuse.

6. In combination, an air break switch, a fusible element connected in shunt of the air break switch, and a liquid dielectric surrounding the fusible element for initially cooling the same when the switch is opened and to extinguish the arc when the fusible element is fused.

7. In a device for interrupting a current flow at high voltage, a switch inherently unable to break the full load flow of current at the desired voltage, a fusible element in shunt of the switch, said fusible element being of a current conducting capacity only a small percentage of that of the current carrying capacity of the switch and being

of a voltage interrupting capacity in excess of the voltage impressed upon the switch and a liquid for cooling the fuse to permit a slight delay in the operation of the same.

8. In combination, a switch, a fuse and means for connecting the fuse across the terminals of the switch, said fuse having means to delay the blowing of the same until after the switch is opened a substantial distance.

9. In combination, a pair of stationary terminals, a switch blade pivoted on one of the terminals, the other of said terminals having contacts for engaging the switch blade, a pair of terminal clips, a fuse mounted in said clips, a non-conducting member connecting said clips and means for connecting the clips to said terminals.

10. In combination, a pair of stationary terminals, a switch blade pivoted on one of the terminals, the other of said terminals having contacts for engaging the switch blade, a pair of terminal clips, a fuse mounted in said clips, a non-conducting member connecting said clips, a pair of connecting members for connecting said clips to said terminals, one of said members being pivoted on one of said terminals and the other of said connecting members being adapted to engage and disengage electrically the other terminal.

11. In combination, a pair of terminals, a switch blade mounted on one of said terminals, a contact mounted on the other terminal, a bar of insulation pivotally mounted on the same axis as the switch blade, a fuse mounted on said bar of insulation and means for connecting the fuse in parallel with the switch.

12. In combination, a pair of terminals, a switch blade mounted on one of said terminals, a contact on the other terminal for engaging the switch blade, a first member pivoted on said one terminal, a second member adapted to engage and disengage the other terminal, a bar of insulation connecting said member, fuse clips electrically connected to said member and a fuse carried in said fuse clips and adapted to be connected in parallel with the switch across said terminals.

13. In combination, a pair of terminals, a switch blade pivoted on one terminal, contact jaws on the other terminal adapted to engage the switch blade, a fuse pivotally mounted on said first one terminal, said fuse being normally connected to said one terminal and contact means adapted to engage the contact jaws on the other terminal, said contact means being connected to the other terminal of the fuse.

14. In combination, a pair of terminals, a switch blade pivoted on one terminal, the other terminal having contact jaws, a fuse

pivottally mounted on the one terminal and having means for engaging the contact jaws on the other terminal to place the fuse in parallel with the switch.

5. 15. In combination, a pair of terminals, a switch blade pivottally mounted on one of said terminals, a fuse also pivottally mounted

on said one terminal, contact jaws on the other terminal, a contact member on the fuse for engaging said contact jaws and for placing the fuse in parallel with the switch.

In witness whereof I hereunto subscribe my name this 7th day of January, 1919.

EDMUND O. SCHWEITZER.
